US00D974381S

(12) **United States Design Patent** (10) **Patent No.:** **US D974,381 S**
Zhou (45) **Date of Patent:** **** Jan. 3, 2023**

(54) **DISPLAY SCREEN WITH GRAPHICAL USER INTERFACE**(71) Applicant: **Google LLC**, Mountain View, CA (US)(72) Inventor: **Bailiang Zhou**, Seattle, WA (US)(73) Assignee: **GOOGLE LLC**, Mountain View, CA (US)(***) Term: **15 Years**(21) Appl. No.: **29/785,850**(22) Filed: **May 27, 2021****Related U.S. Application Data**

(62) Division of application No. 29/674,401, filed on Dec. 20, 2018, now Pat. No. Des. 926,780.

Primary Examiner — Christian P. McLean(74) *Attorney, Agent, or Firm* — Leason Ellis LLP(57) **CLAIM**

The ornamental design for a display screen with graphical user interface, as shown and described.

DESCRIPTION

FIG. 1 is a front view of a display screen with graphical user interface, according to a first embodiment;

FIG. 2 is a front view of a display screen with graphical user interface, according to a second embodiment;

FIG. 3 is a front view of a display screen with graphical user interface, according to a third embodiment; and,

FIG. 4 is a front view of a display screen with graphical user interface, according to a fourth embodiment.

The broken lines form no part of the claimed design. The outer rectangle in broken lines illustrates the display screen and forms no part of the claimed design. The portions of the graphical user interface shown in broken lines form no part of the claimed design.

1 Claim, 4 Drawing Sheets(56)
